Ira L. Nickerson

UNITED STATES PATENT OFFICE.

SAMUEL SEAVER, OF HAILLEYBURY, ONTARIO, CANADA, ASSIGNOR TO CHICAGO PNEUMATIC TOOL COMPANY, OF NEW YORK, N. Y., A CORPORATION OF NEW JERSEY.

HANDLE ATTACHMENT FOR DRILLS.

Application filed May 16, 1925. Serial No. 30,661.

This invention relates to drills of the percussive type used in mining, quarrying and similar development work and more particularly to a handle attachment arranged 5 to adapt a cradle mounted drill for use as a manually supported tool. The invention is in the nature of an improvement upon the demountable handle device disclosed and claimed in the copending application 10 of Forrest H. Blanding Serial No. 725,315 filed July 10, 1924.

Among the objects of the invention are to avoid relative angular movement of handle and drill by providing a more rigid connection between the same, to so arrange the connection that it will not interfere with the quick mounting and demounting of the attachment nor with the action of resilient supports for the handle proper, and in general to improve prior structure in the interests of more efficient and satisfactory service.

In order to illustrate the invention one concrete embodiment thereof is shown in the accompanying drawings, in which:

25 Fig. 1 is a side elevational view of a percussive drill of the cradle or shell mounted type having the present invention applied thereto;

30 Fig. 2 is a right end elevational view of the part shown in Fig. 1;

Fig. 3 is a fragmentary sectional view on the line 3—3 of Fig. 2;

Fig. 4 is a bottom plan view of the parts shown in Fig. 1; and

35 Fig. 5 is a fragmentary sectional view through the drill on the line 5—5 of Figs. 1 and 4 showing the yoke of the handle attachment in side elevation.

The invention is shown as applied to a 40 percussive drill A of the pressure fluid type having parts secured to or integral with the drill cylinder for cooperation with a shell mounting (not shown), such as the projections or wings a and the feed nut a'. The 45 detachable handle device adapting the drill to be manually supported and operated consists of a member or block 6 constructed and arranged to cooperate with the cradle or shell engaging portions of the drill, namely, 50 the wings a, by the provision of the axial grooves or recesses 7 receiving the latter. Block 6 has an end plate 8 forming an abutment for the feed nut a' and a perforation 8' in line with the bore of the feed nut for

the insertion of a clamping bolt 9 by which 55 the block 6 is rigidly secured to the nut and consequently to the drill as indicated. Aligned pairs of perforated ears 10 on block 6 slidingly receive rods 11 which are parallel with each other and with the axis of the 60 drill. Rods 11 have bent ends 11' carrying a handle 12 arranged to dispose the latter in line with the axis of the drill and transverse thereto. Coiled springs 13 encircle the rods on opposite sides of block 6 and 65 yieldingly resist movement of the handle 12 relative to block 6 in both directions. The inner ends of springs 13 engage as abutments the outer faces of ears 10, and the outer ends of the springs engage suitable 70 opposed abutments on the rods, as collars 14 adjacent the handle ends thereof and nuts 14' at the rod ends remote from the handle.

The handle device as heretofore described is substantially identical with that disclosed 75 in the copending Blanding application No. 725,315 mentioned above. In practice it was found that rods of the above described device had a tendency to angular movement relative to block 6 with the latter as a pivot 80 thus subjecting parts of the attachment to undue strain and hampering to a certain extent the directing of the tool. The improvement in the above described handle attachment and constituting the present invention 85 was developed to overcome the above tendency. The invention consists in suitable structure for maintaining the rods 11 in substantially rigid parallelism with the axis of the drill. The preferred means for this 90 purpose, best shown in Figs. 1, 4 and 5, comprise a member 15 carried by the handle structure 11, 12 and movable therewith but maintaining a fixed rectilinear movement of the same in parallelism with the axis of the 95 drill. To this end member 15 takes the form of a yoke having perforated ears 15' through which rods 11 pass and longitudinal grooves or recesses 15" receiving the wings a of the drill (Fig. 5). By preference ears 100 15' are disposed on rods 11 intermediate the lower springs 13 and the stop nuts 14' whereby the springs hold the ears in engagement with the nuts and yoke member 15 is thereby maintained in spaced relation to 105 block 6. Yoke 15 is bowed outwardly as clearly indicated in Fig. 5 to permit the same to pass over the downwardly project-

ing nut a' of the drill when the attachment is being assembled upon the drill. The process of assembling the handle attachment herein described upon the drill consists in 5 aligning the grooves 15" of yoke 15 and grooves 7 of block 6 with the wings a and sliding these parts longitudinally of the drill until abutment plate 8 of block 6 engages feed nut a' . The clamping bolt 9 is 10 then inserted to rigidly secure block 6 in place and the drill is ready to be operated as a manually supported tool.

While what is now considered to be the preferred form of the invention has been 15 herein shown and described it is to be understood that the invention is not limited to the specific details thereof but covers all changes, modifications, and adaptations 20 within the scope of the appended claims.

20 I claim as my invention:

1. The combination with a drill of the cradle or shell mounted type of a handle device for adapting the drill to manual operation comprising a block secured to the feed 25 nut of the drill, a rod slidably mounted upon said block and carrying a handle at one end, resilient means on said rod on opposite sides of said block yieldingly to limit the movement of said rod, and means on said rod 30 engaging the cradle or shell engaging portions of the drill for preventing angular movement of said rod relative to said block, certain of said resilient means being arranged yieldingly to maintain said last 35 named means in spaced relation with said block.

2. The combination with a percussive drill of a handle device for adapting the drill to manual operation comprising a block secured to the drill, rods slidably mounted on 40 said block and extending therebeyond in opposite directions, a handle secured to said rods at one end thereof, coil springs on said rods on opposite sides of said block yieldingly to cushion the movement of the handle relative to the drill, and a yoke connecting the ends of the rods remote from said handle and slidably engaging said drill, certain of said springs maintaining said 45 yoke in spaced relation with said block.

3. The combination with a drill of the cradle or shell mounted type having "wing" 55 portions of a handle device for adapting the drill to manual operation comprising a block and a yoke having recesses slidably receiving said "wing" portions of the drill, means rigidly securing said block to said drill, perforated ears on said block, spaced rods parallel with each other and with the axis of 60 the drill slidable in the perforations of said ears, resilient means limiting the sliding movement of said rods, said yoke being mounted on said rods adjacent one end thereof, and a handle secured to the opposite 65 ends of said rods.

4. The combination with a drill of the cradle or shell mounted type having "wing" portions and a feed nut, of a handle device for adapting the drill to manual operation comprising a block and a yoke having recesses 70 slidably receiving said "wing" portions of the drill, means rigidly clamping said block to said feed nut, aligned perforated ears on said block and on said yoke, rods slidably supported in the perforations 75 of said ears, coil springs encircling said rods on opposite sides of said block, said yoke being mounted upon said rods at one end and engaged by certain of said springs to maintain said block and yoke in spaced relation, and a grip handle secured to the opposite ends of said rods.

5. A handle attachment for percussive drills of the cradle or shell mounted type comprising spaced guide members for engaging 80 the cradle or shell engaging parts of the drill, means for rigidly securing one of said members in place, a handle resiliently mounted on said last named member and carrying the other said member and springs 85 interposed between said members to maintain them in spaced relation.

6. A handle attachment for percussive drills of the cradle or shell mounted type comprising a block for slidably fitting the 90 cradle or shell engaging portions of the drill, means for rigidly securing said block to the feed nut of the drill, means resiliently mounted on said block and carrying a handle, and a yoke carried by said means for 95 slidably fitting the cradle or shell engaging portions of the drill, said yoke being outwardly bowed to enable it to pass over the feed nut of the drill in assembling the 100 handle attachment on the drill.

7. The combination with a percussive tool of the cradle or shell mounted type of a handle detachably secured thereto, said handle having longitudinally spaced guide members 110 engaging the cradle or shell engaging portion of the tool for maintaining the handle against lateral or angular movement relative to the drill, and resilient spacing means between said members permitting movement of one relative to the other.

8. The combination with a percussive tool of the cradle or shell mounted type of a resilient handle device detachably secured thereto, said handle having longitudinally spaced guide members engaging the cradle or shell engaging portions of the tool for maintaining the handle against lateral or angular movement relative to the drill, and resilient spacing means between said members 120 permitting movement of one relative to the other, said means forming at least a portion of the resilient support for the handle.

9. The combination with a percussive tool of the cradle or shell mounted type of a handle detachably secured thereto, said handle 130

having longitudinally spaced guide members engaging the cradle or shell engaging portion of the tool for maintaining the handle against lateral or angular movement relative to the drill, one of said members being secured to said tool and the other to said handle, and resilient spacing means between said members for cushioning the movement of the handle relative to the guide member which is secured to said tool.

10. The combination with a percussive tool of the cradle or shell mounted type of a handle detachably secured to said tool, said handle having a guide member clamped to said tool and a second guide member slidably engaging the cradle or shell engaging portions of said tool for maintaining the handle against lateral movement relative to said tool, and resilient means maintaining said

members in spaced relation and providing a cushion for said handle.

11. The combination with a percussive drill of the cradle or shell mounted type having a feed nut of a handle device therefor comprising a member secured to the feed nut of said drill, a handle mounted for limited sliding movement on said member, means movable with said handle and slidably engaging the cradle or shell engaging portions of said drill for maintaining said handle against lateral movement relative to said drill, and a spring interposed between said member and said means for cushioning the relative movement of the same.

Signed by me at North Bay, Ontario, 35
Canada, this 9 day of May, 1925.

SAMUEL SEAVER.
